UNITED STATES PATENT OFFICE.

THOMAS RAWSON WARREN, OF GLENDALE, CALIFORNIA.

ATTACHMENT FOR GAS OR GASOLENE STOVES.

SPECIFICATION forming part of Letters Patent No. 712,988, dated November 4, 1902.

Application filed November 21, 1901. Serial No. 88,111. (No model.)

To all whom it may concern:

Be it known that I, THOMAS RAWSON WARREN, a citizen of the United States, residing at Glendale, in the county of Los Angeles and 5 State of California, have invented certain new and useful Improvements in Attachments for Gas or Gasolene Stoves; and I do declare the following to be a full, clear, and exact description of the invention, such as will 10 enable others skilled in the art to which it appertains to make and use the same.

The invention relates to an attachment for a gas or gasolene stove.

The object of the invention is to provide a 15 device of this character which shall be simple of construction, durable in use, and comparatively inexpensive of production, and which may be readily attached to the top of a gas or gasolene stove, and which shall be 20 of such construction that the heat from one burner, when but one burner is in use, may be diffused or deflected under the top of the attachment, whereby plates or cooking utensils placed upon the top of said attachment 25 may be subjected to the heat of said burner.

With these and other objects in view the invention consists of certain novel features of construction, combination, and arrangement of parts, which will be hereinafter more 30 fully described, and particularly pointed out in the appended claim.

In the accompanying drawings, Figure 1 is 35 a top plan view of the attachment. Fig. 2 is a cross-section on line *x* *x*, and Fig. 3 is a longitudinal section on line *o* *o*.

Referring to the drawings, 1 denotes the upper plate of a gas or gasolene stove, and 2 the burners, conventionally illustrated.

3 denotes my attachment, which consists of 40 a plate 4, having a surrounding ledge 5, from which depends a marginal flange 6. This ledge is bolted or otherwise secured to the top of a gas or gasolene stove, with the flange embracing the marginal edge or top of the same. 45 The plate is provided with lid-holes 6', which are covered by a lid 7. These lids, which are immediately above the burners, are provided with downwardly-projecting conical deflectors, so that the heat from said burners will 50 be deflected in all directions, thus heating the plates and cooking utensils placed upon

the top of the attachment or in the holes thereof. The lids may be supported in any suitable manner—as, for instance, by riveting to the under side of the top of the attachment short straps or lugs 7'.

The attachment is provided, preferably, with a partition 7², which extends across the same, so that the heat may be confined to one side of the attachment when only that portion thereof is needed in cooking, and thereby saving the heat which would otherwise be deflected or spread under that portion of the attachment not in use.

In order to keep the top of the attachment 65 perfectly straight, I provide a series of spacing-sleeves 8, which are placed between the under side of the top of the attachment and the upper side of the plate of the stove, and through these sleeves and through the top of 70 the attachment and the plate of the stove are inserted bolts 9, the lower ends of which are provided with nuts 10. This construction will hold the top of the attachment perfectly straight and prevent it from sagging or bulging, owing to the heat to which it is subjected.

From the foregoing description, taken in connection with the accompanying drawings, the construction, mode of operation, and advantages of my invention will be readily understood without requiring a more extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

The combination with a gas or gasolene stove provided with burner-openings; of a hollow, flanged, partitioned heating attachment detachably connected to the upper surface portion of the stove and having openings arranged in line with the openings of the stove, and equidistantly-arranged straps connected to the body portion of the attachment having free ends extending part way across the openings of the attachment, and lids adapted to rest on said extended ends of said

straps, and the said lids having downwardly-projecting conical-shaped deflectors to coact with the burners of the stove through the medium of the stove-openings, and adapted to 5 distribute the heat to the hollow portion of said attachment, substantially as and for the purpose specified.

In testimony whereof I have hereunto set my hand in presence of two subscribing witnesses.

THOMAS RAWSON WARREN.
